US0D1056098S

(12) United States Design Patent (10) Patent No.: US D1,056,098 S
(45) Date of Patent: * Dec. 31, 2024

(54) PADEL RACKET

(71) Applicant: STIGA Sports AB, Eskilstuna (SE)

(72) Inventor: Jörgen Lindström Jensen, Eskilstuna (SE)

(73) Assignee: STIGA Sports AB, Eskilstuna (SE)

() Term: 15 Years

(21) Appl. No.: 29/890,119

(22) Filed: Apr. 20, 2023

(51) LOC (14) Cl. 21-02

(52) U.S. Cl.

USPC D21/729

(57) CLAIM

The ornamental design for a padel racket, as shown and described.

DESCRIPTION

FIG. 1 is a front perspective view of a padel racket of the novel design.

FIG. 2 is a front view thereof.

FIG. 3 is a bottom view thereof.

FIG. 4 is a rear view thereof.

FIG. 5 is a top view thereof.

FIG. 6 is a left side view thereof; and,

FIG. 7 is a right side view thereof.

The dashed lines in FIGS. 1-7, if any, represent unclaimed features and form no part of the claimed design.

1 Claim, 4 Drawing Sheets
